(No Model.)

A. HEATH.

GUARD FOR WINDOWS AND DOORS.

No. 361,514.

Patented Apr. 19, 1887.

Fig: 1.

Fig: 2.

UNITED STATES PATENT OFFICE.

ALFRED HEATH, OF JERSEY CITY, NEW JERSEY.

GUARD FOR WINDOWS AND DOORS.

SPECIFICATION forming part of Letters Patent No. 361,514, dated April 19, 1887.

Application filed October 27, 1886. Serial No. 217,343. (No model.)

To all whom it may concern:

Be it known that I, ALFRED HEATH, of Jersey City, in the county of Hudson and State of New Jersey, have invented a new and Improved Guard for Windows, Doors, and Stairways, of which the following is a full, clear, and exact description.

My invention relates to a guard for windows, doors, and stairways, and has for its object to prevent children from falling out of the windows or down the stairways or passing through the doors to which the guard is attached.

The invention consists in the construction and combination of the several parts of the guard, as will be hereinafter fully set forth, and pointed out in the claims.

Reference is to be had to the accompanying drawings, forming a part of this specification, in which similar letters of reference indicate corresponding parts in all the figures.

Figure 1 is a front elevation of the guard as applied to a window, and Fig. 2 a partial plan view thereof. Fig. 3 is a section through the overlapping wire of the guard, illustrating the mode of staying the same, and Fig. 4 is a front elevation of another form of panel. Fig. 5 illustrates a panel formed of single loops.

In describing the construction of my guard I will speak of it only as in connection with a window, but do not limit myself to that special use, as it is equally applicable to doorways, stairways, and other places.

The guard A is constructed of a single piece of wire of a suitable size, formed in a series of loops, B, of various designs, upon a mandrel, the two extreme ends C thereof being either bent over from the top vertically downward, as illustrated in Fig. 1, or up vertically from the bottom, and then parallel downward a distance, so as to resemble the letter U, as shown at D in Fig. 5, the said formation of the ends being more or less governed by the style of loop employed in the body of the guard.

In the further construction of the guard A the continuous loops, formed as above, are passed one over the other, forming thereby a rigid and substantial body, the said overlapping loops at their point of intersection being then submitted to the action of a die, and pro-

vided thereby with the indentations a, as shown in Figs. 2 and 3, the purpose of which is to hold the said overlapping loops in a comparatively fixed position by the interlocking of the said indentations at their point of intersection. 55

The ends of the wire constituting my guard are provided with a thread, b, adapted to receive a nut, e, when the said ends are passed through eyes d, screwed in the sides of the window-frame E, whereby it is held securely in a 6c vertical position.

As a further means to secure the said guard in position and prevent it being raised out of place, screw-hooks h are entered at intervals in the window-sill F and turned over that portion of the guard resting upon the said sill, as shown in Fig. 1. The screw-hooks h are needed only where the intention is to use the guard as a permanent attachment, as the overlapping loops render the same sufficiently 70 strong for ordinary use, and while great rigidity is attained by the above construction the guard is yet to a degree elastic and expansive.

I have shown in Fig. 4 a section of the guard wherein the wire is bent in diamond 75 shape, and in Fig. 5 another section illustrating the application of a series of single loops and the mode of attaching the same. In view of these figures it will be observed that many different forms of loop may be employed in the 80 construction of the body, and the application of the guard will be readily understood from the foregoing description, taken in connection with the accompanying drawings.

I am aware that a fence composed of a single wire formed into loops is not broadly new; and I am also aware it is not new to produce a filling in fences between the posts, consisting of a series of independent metallic rings held in position, one overlapping the other, 90 between two parallel riveted bars extending centrally from post to post and at the bottom by staples entering the lower rail, and I do not lay claim to such.

Having thus fully described my invention, 95 what I claim as new, and desire to secure by Letters Patent, is—

1. A guard for windows, doors, and stairways, consisting of a wire formed in a series of loops and having its ends provided with a 100

screw thread and nut, substantially as shown and described, and for the purposes herein set forth.

2. A detachable guard for windows and the like, consisting of a single wire formed into a series of overlapping loops having indentations *a* at their points of intersection, and

provided with screw-threaded ends and nuts thereon, substantially as herein shown and described.

ALFRED HEATH.
